UNITED STATES PATENT OFFICE.

FRANK B. GRANGER, OF NEW YORK, N. Y., ASSIGNOR TO HALL-BORCHERT DRESS FORM CO., OF NEW YORK, N. Y., A CORPORATION OF NEW JERSEY.

SECTIONAL DRESS-FORM.

1,153,219.

Specification of Letters Patent. Patented Sept. 14, 1915.

Application filed August 8, 1913. Serial No. 783,679.

To all whom it may concern:

Be it known that I, FRANK B. GRANGER, a citizen of the United States, residing at New York, county of New York, State of New York, have invented an Improvement in Sectional Dress-Forms, of which the following description, in connection with the accompanying drawing, is a specification, like characters on the drawings representing like parts.

In my co-pending application Serial No. 783,678, filed August 8, 1913, I have illustrated and described a sectional dress form provided with connecting means for adjustably connecting the sections of the form, which connecting means are situated on the interior of the form but are accessible from the exterior of the form. In the particular embodiment of the invention illustrated in said application, the connecting means are held in their adjusted position by means of a clamping screw, and this clamping screw is so arranged that the head thereof is accessible to the operator from the exterior of the form through an aperture therein.

The object of my invention is to provide a different type of clamping means for the adjustable connections which can also be operated from the exterior of the form but which is provided with a spring clamping device instead of a clamping screw.

The drawings show a selected embodiment of the invention which is sufficient to disclose the principle thereof but I desire to state that the invention is not limited to the constructional features illustrated.

In the drawings, Figure 1 is a front view of the body portion of a dress form embodying my invention; Fig. 2 is a fragmentary view on an enlarged scale of portions of two adjacent sections of the form looking from the inside thereof and showing my improved adjustable connection; Fig. 3 is a section on the line $x-x$, Fig. 2; Fig. 4 is a section on the line $y-y$, Fig. 3; Fig. 5 is a perspective view of the clamping member.

My invention can be applied to any sectional dress form regardless of the particular way in which the form is divided. The

dress form shown in Fig. 1 is divided horizontally across the waist at 2 and horizontally across the bust along the line 3 and vertically either side of the center along the lines 4 and 5, thus producing the hip sections 6, the shoulder and neck sections 7 and the bust sections 8. My improved connecting means for adjustably connecting these various sections together comprises a strap member 9 which is secured to one of the two parts to be connected and a clamping member 10 secured to the other of said parts and provided with a spring-actuated clamp which engages the strap 9. The strap 9 is shown as secured to the form section 6 by means of rivets 11, although this particular construction is not essential. The clamping member 10 is shown as having a foot portion 12 which lies against the inner face of the adjacent form section 8 and is secured thereto by rivets 13, and also a head portion 14 having a slot 15 extending therethrough in which the strap 9 is received. This slot 15 carries a spring-actuated clamp 16 in the form of a plunger which operates in an aperture 17 in the head 14 and is adapted to engage one side of the strap 9 and clamp the latter against the wall of the slot. Means are provided whereby this plunger 16 can be unclamped from the strap 9 from the exterior of the form, and one way of accomplishing this result is to secure said plunger to the yoke-shaped frame 18 which embraces the clamping member 10 and is provided with the portion 19 that is received in a recess 20 formed in one or both of the dress form sections.

A spring 21 is situated between the portion 19 of the clamp and the clamping member 10, said spring operating to yieldingly hold the plunger 16 against the strap 9. As herein shown, the portion 19 of the frame is provided with a recess 22 in which one end of the spring 21 is partially received, said recess operating to hold the spring in its proper position. The yoke-shaped frame 18 will preferably have such a construction that the portion 19 thereof does not project through the dress form thereby to con-

stitute a projection extending beyond the exterior surface thereof, but instead is located entirely within the limits of the dress form sections. The dress form will, therefore 5 present a perfectly smooth surface free from projections which would interfere with the proper fit of a garment.

When it is desired to adjust the dress form, the operator merely pushes inwardly 10 on the thumb piece 19 thereby compressing the spring 21 and carrying the plunger 16 out of clamping engagement with the strap 9. The two sections 6 and 8 can then be 15 adjusted relative to each other and when the desired adjustment is effected, the operator releases the pressure on the thumb piece 19, and the spring 21 automatically brings the clamp 16 into clamping engagement with the strap 9, thus holding the parts in their 20 adjusted position.

My improved clamping means is situated entirely in the inside of the form but is operable from the exterior of the form.

While I have illustrated one embodiment 25 of my invention, I do not wish to be limited to the constructional features shown.

Having fully described my invention, what I claim as new and desire to secure by Letters Patent is:

30 1. The combination with a sectional dress form presenting a shell-like formation divided into a plurality of sections adjustable relative to each other, of connecting means situated entirely on the interior of the form 35 for connecting adjacent sections to each other, said connecting means comprising two overlapping members, one connected to each of the connecting sections, and a spring-actuated frictional clamp engaging 40 one of said members and clamping said members in adjusted position, said form having an opening through which the clamp is accessible to be released.

45 2. The combination with a sectional dress form presenting a shell-like formation divided into a plurality of sections adjustable relative to each other, of connecting means situated on the interior of the form for connecting adjacent sections to each other, 50 said connecting means comprising two overlapping members, one connected to each of the connected sections, and a spring-actuated frictional clamp engaging one of said members and clamping said members in adjusted position, said clamp being operable 55 from the exterior of the form to release its frictional engagement with said member thereby permitting the adjustment of the adjacent sections.

60 3. In a sectional dress form, the combination with two adjacent sections, of connecting means situated entirely on the interior of the form for adjustably connecting said sections, said connecting means com-

prising a spring-actuated frictional clamp 65 for frictionally holding the sections in adjusted position and the form having an opening through which access may be had to the clamp to release the latter.

4. In a sectional dress form, the combination with two dress form sections, of an adjustable connecting means situated on the interior of the form for adjustably connecting said sections, said connecting means comprising a strap secured to one section 75 and a clamping member secured to the other section and provided with a slot through which the strap extends, and a spring-pressed clamp operable from the exterior of the form for clamping the strap to the 80 clamping member.

5. In a sectional dress form, the combination with two dress form sections, of an adjustable connecting means situated on the interior of the form for adjustably connecting said sections, said connecting means comprising a strap secured to one section 85 and a clamping member secured to the other section and provided with a slot through which the strap extends and a clamping 90 plunger carried by the clamping member, a spring acting on said plunger and tending to clamp it against the strap and a thumb piece connected to the clamping plunger and accessible from the exterior of the form by 95 which the plunger can be unclamped from the strap.

6. In a sectional dress form, the combination with two dress form sections, of connecting means situated on the interior of the form for connecting said sections, said connecting means comprising two overlapping members, one connected to each section, and a spring-actuated frictional clamp carried 100 by one member and operable from the exterior of the form for clamping said members in adjusted position.

7. In a sectional dress form, the combination with two dress form sections, of connecting means situated on the interior 110 of the form for directly connecting said sections to each other, said connecting means comprising overlapping members, one connected to each section, and a spring-actuated clamp releasable by inwardly-directed pressure for clamping said members in adjusted position, said form having an aperture 115 through which the releasing pressure can be applied to the clamp from the exterior of the form.

8. In a sectional dress form, the combination with two dress form sections, of connecting means situated on the interior of the form for directly connecting said sections together, said connecting means comprising two overlapping members, one connected to each section, and a spring-actuated clamp for adjustably connecting said sec- 125

tions and provided with a head by which the clamp is released when pressure is applied thereto, the dress form having an aperture to receive said head and permit operation of the clamp from the exterior of the form.

In testimony whereof, I have signed my

name to this specification in the presence of two subscribing witnesses.

FRANK B. GRANGER.
